UNITED STATES PATENT OFFICE.

WILLIAM J. LUTTON, OF PATERSON, NEW JERSEY.

STOP-MOTION FOR LOOMS.

1,158,945.

Specification of Letters Patent.

Patented Nov. 2, 1915.

Application filed July 31, 1914. Serial No. 854,298.

To all whom it may concern:

Be it known that I, WILLIAM J. LUTTON, a citizen of the United States, and resident of Paterson, in the county of Passaic and 5 State of New Jersey, have invented a new and useful Improvement in Stop-Motions for Looms, of which the following is a specification.

My invention relates to a stop motion for 10 looms, with the object in view of providing means for overcoming jar on the loom and the objectionable mark across the goods being woven, resulting from such jar.

The stop motion at present in common 15 use includes a dagger carried by the lay beam, which dagger strikes the frame about the center, thereby causing the beam to spring more or less. The shock also causes the other mechanism, such as the take-up 20 mechanism and warp beam, to move forward which must be accounted for before starting up. The weaver commonly lets back two or three teeth of the roll to accomplish this. The shock given to the lay 25 beam is often so great as to break the frame and other castings of the machine which cannot be replaced without loss of time and considerable expense. If the machine is 30 run at a high speed, the shock will be increased and this has induced the weaver to run at a comparatively low speed, say one hundred and twenty picks to the minute. In the device forming the subject-matter of 35 the present application, the jar is first absorbed by a heavy spring and then by a leather and rubber buffer from whence the shock is transferred to the cast iron ear located upon oscillating arms upon which the lay beam is secured. The lay beam is 40 oscillated by the pitmen which are connected to the ears. It will therefore follow that any shock will be delivered to the beam at the point of the greatest resistance, viz: at the pitmen. I have found that it is entirely 45 feasible to run a loom with the present stop motion installed at a high rate of speed, for example, from one hundred and eighty four to two hundred and four picks per minute.

50 In the accompanying drawings, Figure 1 is a view in side elevation of so much of a loom as will be sufficient to show the present invention in its relation to the parts of the loom which coact therewith. Fig. 2 is an 55 enlarged top plan partly in section. Fig. 3 is a view in side elevation partly in sec-

tion, showing the parts in the positions which they occupy when the stop motion is in action to stop the loom, and Fig. 4 is a similar view showing the position which the 60 parts assume when the loom is working normally.

The loom frame is denoted by 1, the crank 65 shaft for driving the pitmen, by 2, the pitmen by 3 and 4, the lay beam by 5 and the shuttle in position in its box, see Fig. 4, by 6.

The brake band 7, see Fig. 1, engaging a 70 brake wheel 8, is drawn in a direction to put on brakes, by means of a spring 9, whenever the rod 10 is allowed to move to the 75 right, as shown in Fig. 1, by the release of the throw-off lever 11, pivoted at 12, in a part of the frame and held normally in the position shown in Fig. 4, to release the 80 brake band 7 by means of a latch 13 operated by a stop rod 14.

The above parts have been recited without elaboration as they form no part of my present invention except in so far as they coact with the stop motion proper. An arm 15 85 is secured to the ear 15* on the beam 5, the same ear to which the pitman 4 is secured, and extending along the pitman 4 in a direction away from the lay beam 5 and carrying upon the side of its free end a tilting 90 dog 16 pivoted to the arm 15, at 17. The tilting movement of the dog 16 is limited by means of an elongated slot 18, through which a pin 19 extends, the pin 19 being set in the arm 15. The dog 16 is rocked by 95 means of a rod 20 which passes in proximity to a lug 21 on the dog and is provided with a collar 22 located between the lug 21 and an upright extension of the dog, the said 100 rod 20 having its opposite end engaged in limited sliding contact with a tube 23, a spring 24 surrounding the rod 20 being located between the end of the tube 23 and an abutment 25 on the rod 20, said abutment being preferably a nut on a threaded portion of the rod for adjusting the tension of 105 the spring 24. The tube 23 is connected by means of a pintle 26, with an arm 27 carried by a rock shaft 28, extending, in the present instance, transversely across the 110 loom. The arm 27 is provided with a branch 28* in position to engage a sliding block 29 which projects into the shuttle box 30, and which, together with the arm 27, is pressed normally into the position shown in 115 Fig. 3, by means of a bar spring 27*, and which is crowded back, as shown in Fig. 4,

by the shuttle 6 when the latter sets properly in its box 30. The extent of rocking movement of the arm 27, under the action of the shuttle 6 and block 24, is sufficient to tilt the 5 dog 16 into the position shown in Fig. 4. When the dog 16 is tilted, as shown in Fig. 4, its nose will be free to slide over the top of a swinging arm 31, fulcrumed at 32, to a fixed portion of the frame 1. When, however, 10 the dog 16 is allowed to drop, as shown in Fig. 3, when the shuttle 6 is not present in its box, the nose of the dog 16 will be in a position to engage a notch 33 in the swinging arm 31, and cause the latter and the 15 parts connected therewith to move to the right as the drawing is held.

The arm 31 has connected therewith the stop rod 14 for releasing the latch 13 hereinabove referred to, and allowing the throw-off lever 11 to swing into position to put on the brake. The said arm 31 also has connected therewith a spring 34, one end of said spring, in the present instance being connected by means of a thumb nut 35, with 25 a portion of the loom frame and the opposite end connected by a link 36 with the arm 31. The tension of the spring 34 is exerted in a direction to hold the arm 31 swung to the left with the stop rod 14 out 30 of position to release the latch 13, the said arm in this position resting against a leather-faced stop 37. When the said arm 31 is pushed forward by the tilting dog 16, as shown in Fig. 3, to effect a stopping of 35 the loom, its forward movement will be arrested by a stop 38, the face of said stop 38 being provided with a suitable resilient material, in the present instance, a case of leather 39 on a rubber layer 40.

40 In operation, when for any cause the shuttle 6 fails to set itself in the box 30, the arm 27 will be rocked into the position shown in Fig. 3, by means of the spring 24, and the dog 16 will be allowed to drop into 45 the position shown in Fig. 3, with its nose in position to engage the upper end of the swinging arm 31, as the pitman 4 moves the lay beam 5 to the right. This will force the arm 31 to the right against the tension 50 of the spring 34, and against the yielding face on the stop 38, at the same time moving the stop rod 14 to the right, releasing the latch 13 and permitting the lever 11 to rock into position to operate the clutch 41, see 55 Fig. 1, and also to permit the spring 9 to act upon the part 42 to which the brake band 7 is attached, to put on the brake and hence properly stop the loom as the clutch is released.

60 The shock of the impact of the dog 16

against the arm 31 will be at first modified by the spring 34, and subsequently by the yielding face of the stop 38, and will be transferred thence to the point where the arm 15 connects with the pitman 4, where 65 the jarring effect upon the beam 5 will be least.

The device as above constructed is simple, occupies no valuable space, while the spring used for cushioning serves to draw the 70 mechanism back to the position for starting up, thereby eliminating the operation of letting back the take-up roll.

While I have shown the stop motion connected with one of the pitmen, it is to be 75 understood that this may be duplicated with respect to the other pitman, if so desired.

What I claim is:

1. The combination with the lay beam, 80 shuttle, throw-off lever, and means for operating the lay beam, of a tilting dog mounted to move with the lay beam and located back from the lay beam, a spring actuated rocking arm under the control of the shuttle, a yielding connection between said rocking 85 arm and tilting dog, a swinging arm, a stop rod connected with the arm for releasing the throw-off lever, and a spring connected with the swinging arm for receiving the impact of the dog against the vibrating arm. 90

2. The combination with the lay beam, 95 shuttle, throw-off lever and pitman for operating the lay beam, of an arm connected to the lay beam at the point where a pitman is connected thereto, a tilting dog carried 100 by said arm, a rock shaft connected with said tilting dog; means under the control of the shuttle for rocking said shaft and tilting dog, and a yielding cushion in coöperative relation to the said dog and throw-off lever. 100

3. The combination with the lay beam, 105 shuttle, throw-off lever and means for operating the lay beam, of a movable part in position to be operated by the shuttle, a tilting dog in position to be operated by said movable part, a swinging arm in coöperative relation to the tilting dog and throw-off lever, a spring tending to draw the swinging arm in a direction against impact of the tilting dog and a yielding faced stop 110 in position to arrest the movement of the swinging arm in the opposite direction. 110

In testimony, that I claim the foregoing as my invention, I have signed my name in presence of two witnesses, this eleventh day 115 of July, 1914.

WILLIAM J. LUTTON.
